AUTOMOBILE

Ernest W. Baxter, Van Wert, Ohio

Application January 31, 1957, Serial No. 44,688

Term of patent 7 years

(Cl. D14—3)

Fig. 1 is a perspective view of an automobile embodying my new design.

Fig. 2 is a front elevational view thereof.

Fig. 3 is a side elevational view thereof the side opposite that shown being substantially the same.

Fig. 4 is a sectional view along the lines 4—4 in Fig. 1.

Fig. 5 is a sectional view along the lines 5—5 in Fig. 1.

Fig. 6 is a sectional view along the lines 6—6 in Fig. 1.

The dominant features of my design are those portions shown in solid lines.

I claim:

The ornamental design for an automobile, substantially as shown and described.
